4 Claims. (Cl. 57—54)

1

This invention has reference to wire stranding, rope and cable making machines of the kind in which a tubular frame, having openings in its walls, is rotated by mechanism at one end which twists strands together into a rope or cable, the strands being drawn through guide eyes on the tubular frame from bobbins mounted in cradles inside the tubular frame and which do not rotate with the frame.

In machines of this kind the bobbins are situated one behind the other in their cradles and are carried on spindles which are easily removed from, and inserted in, the bobbins and on which they rotate as the strand is drawn off from them and the stranded rope or cable is wound up on a haul-off drum at the twisting end of the tubular frame.

The mounting of the bobbins in the tubular frame is a matter of difficulty and often takes considerable time as the bobbins are heavy and are indeed often of great weight, and it is a serious matter when a large and expensive machine has to be stopped for any lengthy period while the bobbin mounting is done; it is therefore highly desirable to reduce the stopped time as much as possible.

There are only two directions in which the bobbins can be mounted and dismounted, namely by lowering them through the openings in the tubular frame or raising them from below. To lower them means that over-head tackle must be used to lift the bobbins, carry them along the machine to the desired place and then lower them exactly into place where the spindle can be inserted and then lower them further into place; the difficulties in doing an operation of this kind with a swinging tackle will be easily appreciated.

To overcome this difficulty it has been proposed to mount the bobbins from below and to this end rail sections have been mounted below the tubular frame and under each cradle a platform has been provided on which the bobbins can rest, the platform being raised and lowered by a hand operated wheel at one side of the machine working through chain tackle and snatch blocks so that the platform is pulled up to the desired position for insertion and removal of the spindle after which the full bobbin is lowered into the cradle or the empty one is lowered to the rails.

This mechanism while having advantages over the use of overhead tackle has disadvantages such as the complicated nature of the chain tackle which hangs down at both sides of the machine near every cradle, and the manual operation is still slow and heavy.

2

The present invention has for its object to provide an improved means for lifting the bobbins into the tubular frame which will be simpler in construction and operation and will not have any chains or hanging gear, such as has the existing types of gear.

According to the invention a wire stranding or rope or cable making machine of the kind referred to and having a track below the tubular frame for use in upward loading, is provided with a platform or platforms carried on transverse members across the track and pushed upward from below by a power lifting device such as a jack, the bobbins which run along the track being stopped over the platform and centered thereon in the position exactly required and lifted into position or conveniently lowered and rolled away when empty.

The invention is more particularly set forth with reference to the accompanying drawings wherein—

Fig. 1 is a side elevation of a machine according to the invention.

Fig. 2 is a sectional elevation on the line 2—2 of Fig. 1 and

Fig. 3 is a plan of a portion of the track showing the lifting gear.

As shown in the drawings bobbins 4, only one of which is shown in the drawings, are mounted detachably on spindles 5 carried in bearings 6 in the cradles 7 inside the rotatable tubular frame 8, the frame rotating round the cradles, the wire being drawn off the bobbins, through eyes—not shown in the drawing—in the tubular frame along which the strands are passed to the right-hand end in Fig. 1 where they are twisted and wound on to a haul-off drum.

Below the tubular frame 8 is a track 9 extending from end to end of the machine along which the bobbins 4 can be run, and in the track 9, below the bearings 6 for the bobbin spindles 5, centering stops 10 are provided in the form of slots in the track to arrest the bobbins as required when they are rolled along the track.

On each side of these stop positions, slots 11 are made in the track and beneath them are transverse members having upstanding and inwardly bevelled edges which pass from one side of the track to the other, the transverse members being connected by a plate or base 13, thus giving them, in plan, the appearance of the letter H with a thickened cross piece.

When the bobbin 4 is brought to rest it lies with its axis substantially parallel to the transverse members 12, as shown in the drawings, and

if these are raised so as to lift the bobbin it will automatically drop or settle into an exactly parallel position and lie on the transverse members 12 as in a cradle, and the central hole of the bobbin will be vertically below the detachable spindle 5 in the cradle spindle bearings 6 above, in addition the bevelled edges of the transverse members 12 will centre the bobbin across the track so that if the bobbin be raised to the correct height when the tubular frame 8 is turned so that one of its 10 openings 14 is underneath, it will pass upward through the centre of the opening and its central hole will be exactly aligned with the bearing holes so that the spindle 5 can easily be slid through, thus quickly mounting the bobbin in the bearings 6.

In order to lift the bobbin, and to have no impediment to the quick insertion of the spindle, and of course removal of the spindle when the bobbin is empty, the transverse members 12 are 20 lifted from below by mechanism such as a jack 15 which may be hydraulic, or mechanical, and which operates under the plate or base 13. There may be one jack fixed in place under each pair of transverse members, all provided with power from a suitable source, each being individually operated by a pedal 16 or by other convenient means.

If desired, instead of having a fixed jack at each position a movable jack may be used, in which event means are provided to ensure the correct centering of the jack under each pair of transverse members so that the lift is always central and vertical on the centre. In this arrangement, instead of mounting the transverse members across the track at positions under each bobbin cradle, gaps may be made in the track and the transverse members mounted permanently on a movable jack so that the whole lifting gear can be put into place as and when required and the transverse members pushed up through the gaps in the track by the jack or other lifting device used.

It will be appreciated that while the invention has been described herein with reference to the mounting of bobbins, the mechanism is also used in the reverse manner for the equally important work of removing the empty bobbins which, even when empty, often have a considerable weight, and are awkward to handle and manipulate.

In order to avoid accidents while the bobbins are being mounted and dismounted it is very necessary that the tubular frame 8 should remain quite still and a trip device such as 17 is provided which cuts off the main driving motor of the machine, such machines being usually driven by an electric motor, as soon as, and as long as the transverse members are lifted and which only closes the circuit again when the transverse members are fully down.

As shown in Figs. 2 and 3 there may be at intervals along the machine, side loading or unloading runways 18, which facilitate the loading and unloading of the bobbins by making it possible to put them on and take them off without the need for running them the whole length of the track

9, and to this end the platform or the head of the jack or lifting device may be adapted to turn.

What we claim as our invention and desire to secure by Letters Patent is:

1. A wire stranding, or rope, or cable, making machine, comprising a rotatable tubular frame, bearings supporting said frame, means for rotating said frame, bobbin supports in said frame, a track below said frame on which bobbins can be run to positions, said frame having openings below said bobbin supports to allow access from below to said bobbin supports, transverse members across said track below each of said bobbin supports, platforms carrying said transverse members, a power lifting device below said platform and supporting it, by which bobbins on said transverse members can be raised to, and lowered from, said bobbin supports in said frame.

2. A wire stranding or rope or cable making machine comprising a rotatable tubular frame, bearings supporting said frame, means for rotating said frame, bobbin supports in said frame, said frame having openings to provide access to said bobbin supports, a track below said frame on which bobbins can be run, transverse members across said track below said bobbin supports, arresting means and centering means on said transverse members to arrest and center a bobbin below said bobbin supports, a platform below said transverse members, said platform being rotatably mounted on a power lifting device below said platform, side runways at one side of the track on to which empty bobbins can be run from said transverse members when said platform is turned at right angles to its normal position.

3. A wire stranding or rope or cable making machine comprising a rotatable tubular frame, bearings supporting said frame, bobbin supports in said frame, a track below said frame on which bobbins can be run, said frame having openings to allow access to said bobbin supports from below, electrically-operated mechanism for rotating said frame, transverse supports for said bobbins across said track, a platform under said transverse supports, lifting means below said platform, an electric switch in the circuit of said electrically operated mechanism for rotating said frame, said switch being opened by the raising of said platform, and closed by its regaining its lowest position, whereby said frame cannot be rotated by said electrically operated mechanism when said platform is raised.

4. A wire stranding or rope or cable making machine comprising a rotatable tubular frame mounted in end and intermediate bearings, a track below said frame on which to run bobbins, transverse members at intervals across said track, a platform under said transverse members on which they are mounted, and a lifting jack below said platforms for raising and lowering said platform.
